DENTAL CHAIR OR SIMILAR ARTICLE

John M. Gardella and Rudolph Vetere, Staten Island, N.Y., assignors to The S. S. White Dental Manufacturing Company, Philadelphia, Pa., a corporation of Pennsylvania

Filed July 27, 1965, Ser. No. 86,309

Term of patent 14 years

(Cl. D15—3)

FIG.1

The dominant features of the design reside in the portions shown in full lines.

We claim:

The ornamental design for a dental chair or similar article, as shown and described.
